UNITED STATES PATENT OFFICE.

AUGUST E. SCHUTTE, OF NORTHBORO, MASSACHUSETTS, ASSIGNOR TO WARREN BROTHERS COMPANY, OF CAMBRIDGE, MASSACHUSETTS, A CORPORATION OF WEST VIRGINIA.

MACHINE FOR MAKING CONCRETE ROADWAYS.

Application filed May 22, 1924. Serial No. 716,724.

My improvement relates to machines more especially adapted to be used in laying concrete and finishing concrete roadways and foundations, i. e. for pavement whether for use by vehicles or by walkers. In the methods heretofore used in paving such roadways tamping, screeding or belting have been the common methods of settling and binding the concrete into place. Tamping especially results in bringing the mortar, the water and the cement which float up with it to the surface of the layer of concrete so that the larger stone which should take the wear of traffic is scarcely exposed to such wear, but is covered by a more or less thin coating of cement and sand or small stones; and when thoroughly set this soft mixture soon chips off leaving a rough uneven wearing surface which offers new sources of disintegration.

My invention is a machine for finishing a concrete surface and is so constructed as to do this intermittently and progressively so that while but a small portion of the surface is acted upon at a time, the arrangement of its finishing members is such that a longitudinal wiping pressure is given to the entire surface piecemeal to drive the larger stones into place without crushing and push out of the way surplus material, thus giving an intermittent and progressive pressure so that the larger particles are forced into place and fitted together with a more or less contacting relation to each other leaving a minimum amount of mortar between them and on the surface and permitting a great deal drier mixture to be used, thus not only binding the particles closer together, but eliminating to a considerable extent the air cells which are left by the evaporated water. It is well known that the less water used in mixing concrete (i. e. the drier the mixture), the denser, stronger and more uniform it will be. The wetter the mixture, the more segregation.

It is obvious that this machine and process can be equally well applied to bituminous and other plastic mixtures, in which case the mortar may be a bituminous or other cement which is in a plastic condition at the time when the levelling and compressing machine is applied.

My invention will be understood by reference to the drawings in which it is shown in its preferred form.

Figure 1 is a plan of the machine embodying my invention;

Fig. 2 being a side view thereof, the engine being omitted.

Fig. 3 is a section on line 3—3 of Fig. 1.

Fig. 4 is a section on line 4—4 of Fig. 1, showing the finisher.

Figs. 5 to 8 are details described below.

Fig. 9 is a section on line 9—9 of Fig. 1, showing diagrammatically the relative arrangements of the various wipers of the finisher.

Figs. 10 and 11 are diagrammatic views showing a way of supporting the apparatus in operation.

My machine comprises a car having a frame the side portions of which are numbered 1 and 1^a, the end portions 2 and 2^a and its braces 21 and 21^a, these several parts being of any convenient size and shape in cross section. The frame is supported on four wheels *a*, the axles 4, 41 of which extend across the car and are journaled in bearings 3, 31, mounted on the under side of the side beams 1, 1^a. 5 is a motor of any suitable character having a power shaft 6 carrying a sprocket wheel 7 which is connected by a sprocket chain 8 running around a sprocket wheel 9 on the end of the finisher shaft 10. By this means the shaft 10 and the finisher are given a continuous rotation.

Power is applied to move the car as follows: At the further end of the finisher shaft 10 is a spiral gear 15. From the side of the side frame 1 project brackets 12 in each of which is mounted a shaft 13, 14. The shaft 13 carries a spiral gear 11 meshing with the spiral gear 15. The shaft 14 has at its further end a worm 16 meshing with the worm gear 17 on the end of the shaft 41. The shafts 13 and 14 are connected by a clutch 18 operated by a handle lever 19 in a usual way. This construction is such that when the members of the clutch 18 are engaged power will be transmitted from the shaft 10 through the shafts 13 and 14 to the shaft 41 to give power to drive the car. When the clutch members are disengaged, as by means of the lever 19, the shafts are disconnected and power to drive the car will be shut off. These parts

are so constructed and arranged that the finisher and the car wheels are revolved in different directions.

The motor 5 is of such construction that the machine may be driven either forward or rearward as desired.

At the front end of the machine there are mounted graders which as shown comprise four scrapers preferably attached together, of which the scraper 20 is bolted both to the side beam 1 and a brace 21. The scraper 22 is bolted also to the brace 21 and its outer end is strapped as shown at 223 or connected in any convenient way to the scraper 23 which in turn is bolted to the brace 21^a. The scraper 24 is bolted both to the brace 21^a and the frame 1^a. It will be noted that these scrapers are arranged at an angle to each other and that the outer scrapers 20 and 24 are placed to guide the material which may strike them in a general direction to keep all such within reach 20 of the finisher.

In order to adjust the height of these scrapers, the bolts 25 by which they are attached to the frame, etc. pass down through the frame and through collars 27, one on 25 each side of the frame, and into threaded castings 26 mounted on the scrapers. The collars 27 are attached to the bolts 25 so that in the rotation of the bolts their position with relation to the frame will not be 30 changed, but as they are turned the scrapers may be lifted or lowered as occasion may require (see Fig. 3).

The finisher, which is the important element in this machine, comprises a series of 35 wipers 31 mounted to wipe the upper surface of the graded concrete so as to press into place all the material possible and push forward and generally downward other material in front of them by a wiping action 40 which shall leave a smooth surface behind them.

As shown these wipers are each preferably mounted on the periphery of a disk 28 at the greatest distance from its axis. These disks 45 are of the same diameter and are mounted eccentrically on the shaft 10 and keyed thereto by a key or keys 29 so that they will be rotated positively by the shaft. Each wiper 31 is preferably of steel and is mounted on that part of the periphery of the disk which will touch the concrete. These disks 50 28 are in pairs and the two members of each pair are so placed with relation to each other that their wiping part is approximately 180 55 degrees from each other and each pair is staggered on the shaft with relation to the next pair. In Figs. 7 and 8 two pairs of disks are shown and the pairs of disks in Figs. 7 are at a slight angle to those in 60 Fig. 8. In each disk there is a hole 29 to receive the shaft, which hole has a key seat 30 to receive the key 29^a.

The machine in the drawings shows two sets of pairs of disks 28 on the same shaft 10, each set running from the centre to the

end of the shaft. This will be apparent by comparing Figs. 1 and 4 where there are shown 36 disks, 18 in a set. In Fig. 1 the two end disks are in similar positions. This is a good arrangement for a machine say 70 nine feet wide, but other arrangements may be used. In no two disks of the same set are the holes 32 and key seats 40 in the same part of the disk. There is enough variation in their positions to bring the wipers in 75 proper relation to each other.

Each wiper 31 is wider than its disk so that as shown in Fig. 6 it extends laterally a short distance on each side of the disk to overlap the joint between each disk and 80 the next one to it and this not only prevents the fine particles of concrete from getting into the cracks between adjacent disks, but also secures a better concrete surface.

In order that the car may be made to go 85 around a curve, provision is made for adjusting the angle of the front axle 4 to the body of the car. For this purpose the bearings 3 are slidably attached to the hangers 3^a. Each bearing has a socket piece 33 90 mounted thereon and a screw 34 which passes through threaded collars 32 on said hangers, and a handle 35 is also provided, one end of the screw being fastened in any suitable manner in the socket 33 so that the end of 95 the screw will be held therein, but allowed to turn, the other end of the screw carrying the handle 35. It will be seen that by turning the handle 35 the corresponding end of the axle 4 will be pushed either forward 100 or rearward according to the direction in which the screw 34 is turned and hence the axle will be caused to lie at an angle with the rear axle such that the car as a whole will easily move around any curve. This axle-adjusting means may be provided at both sides 105 of the car as shown, though under certain conditions a single one of these appliances may be used.

The apparatus therefore may be adjusted 110 according to the direction in which it is passed along the road. The graders may also be adjusted vertically, if required by circumstances, and the machine may be stopped at any moment by disconnecting the shafts 115 13 and 14 by means of the clutch 18.

Preferably and as shown, the bearing wheels *a* are provided with two flanges so as to straddle a rail 40, 40^a, and in practice two rails, preferably channel iron, are first 120 laid and spiked one on each side of the space to be covered with concrete and preferably these rails are laid so that their tops are approximately the thickness of the concrete above the foundation, and serve as 125 side or retaining walls to prevent the concrete as it is being laid from spreading beyond the reach of the machine. A length of these rails, say a few hundred feet, is first laid on the roadbed or foundation and pref- 130

- erably tie bolts 41 are used to connect them together at suitable points, the tie bolts being removed from time to time ahead of the car and after the concrete has set more or less the spikes and rails are removed for use elsewhere. The machine as a whole is made approximately the width of the surface to be concreted, which is usually about nine feet, and if the finished concrete surface is to be very wide, a single rail 40 on the outside edge of the second strip and the finished edge of the roadbed are used to support the inner wheels, which in this case are ordinary unflanged wheels (see Fig. 11).
- To lay a roadway with this machine, a quantity of concrete is dumped in piles in front of the graders and the machine is started up. The properly adjusted graders being in front level off the piles and spread the concrete, the surplus material being kept between the rails on which the car travels. The next action is that of the wipers 31 on the finishing roll which finishes, compresses and wipes off the concrete, and immediately follows the grading action. As is stated above, this roll comprises a series of wipers which overlap in their action and being staggered about the shaft 10, as each wiper wipes the surface, the wiper of the next disk is approaching the surface and takes up the wiping operation where the adjoining wiper has left it. The shaft carrying these wipers is rotated in the opposite direction to that of the car wheels so that each wiper pushes forward longitudinally the surplus material in front of it and leaves a wiped surface behind it, compressing the stone aggregate of the concrete with which it contacts into place causing it to push the adjacent material out of the way. Thus a place is made for the stone between its neighbors, and the wiping action smoothing off the top surface of the concrete, the stones are thus brought into contact and cemented together by the cement. The action of one wiper is supplemented by the action of the wiper next to it, which crowds down any stone which the first wiper has pushed out of its way as well as the material in front of it, the wipers, as stated above and as shown in Fig. 6, overlapping somewhat so that the surface is left by the finishing roll substantially smooth and with substantially no lines of demarcation to show where the several wipers have left their working pressure.
- A machine which has been constructed has worked well with disks eight inches in diameter and car wheels about ten inches in diameter and operated at a rate of about three feet of travel a minute, the speed of rotation of the finishing roll being considerably greater than that of the car wheels. For example, three rotations of the finishing roll to one rotation of the car wheels have been found to be effective.
- If the weight of the car is not sufficient to give proper pressure to the concrete the car may be weighted in any way as, for example, by a platform and rocks.
- It is evident that my invention may be otherwise embodied than as shown in the drawings, its main feature being the rolling of the concrete intermittently, progressively and longitudinally, that is to say, wiping the stone longitudinally down into place with a pressure which is applied to small areas of plastic material at a time and almost immediately thereafter to adjacent areas so that the work progresses in sequence across the surface, and any portion of the material which is left unfinished at the side of one wiper is immediately compressed into place by the next wiper.
- In using the word "longitudinally" I mean in the direction in which the car is traveling.
- I use the word "concrete" in its broad sense meaning a mineral aggregate cemented together by any suitable cement, non-bituminous or bituminous.
- What I claim as my invention is:—
1. A machine to finish a plastic surface comprising a car and means for moving it and having finishing means mounted thereon, said finishing means comprising a series of rotary independent non-yieldable wipers mounted side by side on the same axis and means for mounting and operating them whereby they will engage the surface of the concrete and compress it and wipe therefrom surplus material.
  2. A machine of the kind described comprising a car and means for moving it and movable compacting means mounted thereon, said compacting means comprising a weighty finishing member whereby the material to be acted upon will be progressively compressed and wiped downward into place and any surplus material will simultaneously be wiped off.
  3. A machine of the kind described comprising a car having movable compacting means mounted thereon, said compacting means comprising a sectional rotary finishing member, said rotary member comprising a rotary supporting member having a series of wipers mounted in pairs progressively side by side thereon in staggered relation to each other, whereby each in turn will compress and wipe the surface of the material acted upon.
  4. A machine of the kind described comprising a car having movable compacting means mounted thereon, said compacting means comprising a sectional rotary finishing member, said rotary member comprising a rotary supporting member having a series

of disks mounted eccentrically side by side thereon in staggered relation to each other, each disk having a shoe mounted on its periphery at points farthest from its axis of 5 rotation.

5. A machine of the kind described comprising a car having a movable compacting means mounted thereon, said compacting means comprising a sectional rotary finishing means, said rotary means comprising a rotary supporting means having a series of disks mounted eccentrically side by side thereon in staggered relation, each disk having a shoe mounted on its periphery at points 10 farthest from its axis of rotation and each shoe being wider than the thickness of its disk, whereby each shoe in turn will compress the material with which it comes in contact with a wiping action and will overlap the work done by the shoes on each side 15 of it.

6. A concrete-road-finishing machine comprising a movable car and means for moving it, means for compacting the surface of the 20 road and graders mounted on one end of said 25 car,

car, said graders comprising V-shaped members connected together at their adjacent ends having their outer portions advanced further from the front line of the car than their inner portions, whereby in grading 30 they will throw the surplus material engaging them within the path of said compacting means in combination with means for compacting said surplus material.

7. A concrete-road-finishing machine comprising a movable car and means for moving it, means for compacting the surface of the road and graders mounted on one end of said car, said graders comprising V-shaped members connected together at their adjacent ends having their outer portions advanced further from the front line of the car than their inner portions, whereby in grading 35 they will throw the surplus material engaging them within the path of said compacting means, and means for altering the level of said graders in combination with means for compacting said surplus material.

AUGUST E. SCHUTTE.
